(57) **CLAIM**

The ornamental design for a glass water dispenser, as shown and described herein.

DESCRIPTION

FIG. 1 is a front, right side perspective view of a glass water dispenser, showing our new design;

FIG. 2 is a front view of the glass water dispenser of FIG. 1.

FIG. 3 is a rear view of the glass water dispenser of FIG. 1.

FIG. 4 is a left side view of the glass water dispenser of FIG. 1.

FIG. 5 is a right side view of the glass water dispenser of FIG. 1.

FIG. 6 is a top view of the glass water dispenser of FIG. 1; and,

FIG. 7 is a bottom view of the glass water dispenser of FIG. 1.

The broken lines in the drawing views represent environmental structure and form no part of the claimed design.
